UNITED STATES PATENT OFFICE.

FRANCIS McCUTCHEON AND JOHN J. MOSSOP, OF PHILADELPHIA,
PENNSYLVANIA.

DESIGN FOR A SCARF-PIN.

SPECIFICATION forming part of Design No. 32,649, dated May 15, 1900.

Application filed April 19, 1900. Serial No. 13,551. Term of patent 3½ years.

To all whom it may concern:

Be it known that we, FRANCIS McCUTCHEON and JOHN J. MOSSOP, citizens of the United States, residing in the city of Philadelphia, in 5 the State of Pennsylvania, have invented and produced a certain new and original Design for a Scarf-Pin, of which the following is a full, clear, and exact description, reference being had to the accompanying drawings, forming 10 a part of this specification.

In said drawings, Figure 1 is a front elevation, Fig. 2 a side view, and Fig. 3 a rear view, of our new scarf-pin.

Our invention relates to the shape or configuration and to the novel appearance of the 15 article; and it consists of the design therefor shown in said drawings.

The distinguishing features are a pin *b*, a disk *c*, a centrally-projecting spindle *d*, and a disk *e*, formed of radially-projecting blades 20 *e'* to give it somewhat the appearance of an electric fan.

We claim as new and of our invention—

The design for a scarf-pin, substantially as shown and described. 25

In testimony whereof we have hereunto affixed our signatures this 16th day of April, A. D. 1900.

FRANCIS McCUTCHEON.
JOHN J. MOSSOP.

Witnesses:

WALTER C. PUSEY,
H. T. FENTON.
